UNITED STATES PATENT OFFICE.

GOTTLIEB DAIMLER, OF CANNSTADT, WÜRTEMBERG, GERMANY.

MOTOR-ENGINE.

SPECIFICATION forming part of Letters Patent No. 349,983, dated September 28, 1886.

Application filed May 13, 1885. Serial No. 165,390. (No model.) Patented in England April 7, 1885, No. 4,315; in Belgium April 30, 1885, No. 68,536; in Austria-Hungary July 10, 1885, No. 13,745 and No. 35,256; in Spain July 21, 1885, No. 5,021; in Italy August 27, 1885, No. 18,747, and in France September 16, 1885, No. 168,279.

To all whom it may concern:

Be it known that I, GOTTLIEB DAIMLER, a citizen of Würtemberg, residing at Cannstadt, in the Kingdom of Würtemberg and Empire 5 of Germany, have invented new and useful Improvements in Motor-Engines Worked by Combustible Gases or Petroleum Vapor or Spray, (for which I have obtained patents in Belgium, No. 68,536, April 30, 1885; Austria- 10 Hungary No. 13,745 and No. 35,256, July 10, 1885; Spain, No. 5,021, July 21, 1885; Italy, No. 18,747, August 27, 1885; France, No. 168,279, September 16, 1885, and Great Britain by application No. 4,315, April 7, 1885,) of 15 which the following is a specification.

My invention relates to an improved construction of that class of motor-engines worked by combustible gases or petroleum vapor or spray wherein a combustible charge is only 20 introduced at every alternate instroke of the piston, the improvements being such that the gaseous charges employed are of greater volume and are freer from products of combustion than those of engines heretofore constructed. This is effected by introducing into 25 the cylinder, both before and after the admission of the main charge of gaseous mixture, additional charges of either combustible mixture or of air introduced at every stroke by 30 means of a pump formed in the working-cylinder on the side of the piston opposite to that on which the charge works. By one of these additional charges the products of combustion are at the same time driven out of the cylinder. The ignition of the charge is prevented 35 from taking place until the crank is at the dead-center by causing an explosive mixture poorer in gas than the cylinder-charge to 40 come in contact, while compressed, with a heated part of the admission-passage, the moment of ignition being regulated by varying the proportion of gas in the igniting-mixture. A further improvement relates to the mode 45 of regulating the speed of engine, this being effected by bringing the valve-gear to a standstill when the normal speed is exceeded, the gaseous products of combustion being made to remain under pressure in the cylinder, so that no fresh charge is admitted.

Figure 1 of the accompanying drawings 50 shows a vertical section of an engine invented by me for carrying my invention into effect. Fig. 2 shows a part elevation and part section at right angles to Fig. 1. Figs. 3, 4, 5, and 6 show details.

A is the working-cylinder with compression-space A', at the upper end of which is the inlet and discharge passage a.

b is the inlet-valve for the combustible charge; c, the discharge-valve; and d is a tubular extension on the inlet-passage, heated externally.

E is the piston with the inlet-valve e, spring e', and contact-plate e".

F is a forked projection fixed to the framing, with which fork the plate e" comes in 65 contact toward the end of each instroke of the piston, so as to force back the spring e', and thus cause the valve e to be free and automatic in its action during a certain time before and after the dead-center of the instroke of the 70 piston, so as only to open when the pressure in the crank-chamber exceeds that in the cylinder.

G is the gas-tight crank-chamber with inlet-valve g' for combustible mixture, or for air 75 alone, and cover g", which latter is made sufficiently large to enable the crank-plate, with its shaft, to be taken out of the chamber.

H' H" are crank-plates, that can be made heavy, so as to serve at the same time as fly-wheels, and which occupy the greater part of the chamber, in order to make the pump-chamber in the same as small as possible, and thus to obtain a compression in the same of from one-fifth to one-half atmosphere over-pressure.

In order to simplify the machine, one of the crank-plates might be omitted. The valve-gear is actuated by a cam-groove, k k', formed in the crank-plate H', and which passes twice 90 round the crank-shaft and returns into itself, and in combination with which is the sliding block o and the rod L, which acts upon the rod c' of the escape-valve c. It will be seen that the cam-groove k k' is so formed that at 95 one revolution of the crank the sliding block o is moved from the groove k into the groove k', whereby the rod L is withdrawn from the

rod c' of the escape-valve c , which consequently remains closed during the corresponding in and out strokes of the piston. At the next revolution of the crank the block o is moved 5 back from the groove k' into the groove k , whereby the rod L , in rising, is made to open the escape-valve, such opening being effected after the piston has performed its working-in-stroke. The groove k' is circular, and is connected by branches, as shown, with the groove k , by means of which the block o is made to pass from the one to the other.

The regulation of speed is effected by means of the governor-arm m , with spring centrifugal action, and the switch n , which, on the normal speed being exceeded, move out of the working position at Fig. 2 into the position at Fig. 3, whereby the block o is caused to remain in the cam-groove k' during the rotation 10 of the crank, and the rod L is thus brought to a standstill, until by the reduction of speed the switch is again moved back to the position at Fig. 2. The governor m is suspended from the axis i , and has a spring action in the direction of rotation round this point. The switch n is formed with an incline, and is connected to the axis i by its extension, which has a spring action at right angles to the axis, as shown at Fig. 4, in order that in the event of 15 the two edges n' o' meeting they may escape one another, so as to allow o to pass on the one or the other side of n . The governor m is pressed inward by a spring, u , in the contrary direction to the centrifugal force due to the 20 speed of rotation.

The ignition of the charge is effected by the compression of the charge by means of the working-piston, whereby a certain part of the charge is brought, in a compressed condition, 25 in contact with the tubular extension d , heated externally by a gas flame. In order to retard this ignition until the crank is on the dead-center at the compressing-outstroke, the last portion of the charge of combustible mixture 30 is reduced in strength from one-third to one-half that of the main charge, so that the passage a and tube d will only contain such weak mixture during the compressing-stroke.

The weak charge is produced by the action 35 of the gas-valve q , which toward the end of the suction-stroke is pressed downward by the arm l of the valve-rod, and thus restricts the passage of gas. By the adjustment of the screw S the strength of the charge, and consequently the moment of ignition, is accurately regulated.

The temperature of the cylinder can be kept tolerably high, and, in the absence of water, sufficient cooling can be effected by a moderate 40 current of air through the surrounding jacket.

The engine is started by rotating the crank-shaft by means of the crank-handle r , attached to the belt-pulley w , the discharge-valve c and 45 suction-valve g being opened, this being effected by placing the support p under the stop on the valve-rod c' , and by screwing inward

the screw t , so as to open the valve g . The crank-handle is drawn out when the engine is started.

The mode of operating is as follows: Just before the end of the working-instroke the discharge-valve is opened, the pressure in the cylinder sinks below that in the pump-chamber, the piston-valve e opens automatically in this position, and admits a charge of combustible mixture, under pressure, or of air into the cylinder, which drives the products of combustion out in front of it. By the outstroke of the piston, and by the charge of mixture or air forced in, the lighter products of combustion situated in the upper part of the cylinder are expelled through the discharge-valve. The combustion-space of the cylinder is now charged with combustible mixture or air. To 50 this preliminary charge is now admitted, during the instroke of the piston, the main charge entering through the admission-valve b , such charge consisting of air mixed with either gas or petroleum in the form of vapor or spray. During the first part of the instroke the piston at the same time compresses the combustible charge or air drawn in beneath it into the pump-chamber until shortly before the end of the stroke, when the piston-valve r is rendered free in its action again, and the third portion of the charge now passes from the pump-chamber into the cylinder until the pressure in the two are equalized. At the second outstroke of the piston the total charge is 55 further compressed, and is ignited, as above described, when the end of the stroke is reached.

The above-described mode of operating may be varied by omitting either the preliminary charge or the supplemental charge of combustible mixture or air. For this purpose the admission-valve g' to the crank-chamber would be arranged on the cover g'' beneath the rod L , that actuates the discharge-valve, and for the first-mentioned case, where the preliminary charge is to be omitted, the rod L would be made to hold the valve open by means of a loop, L' , while it is rising during the working-instroke of the piston, as shown at Fig. 5, so that the charge of combustible mixture or of air that had previously been drawn in through the valve g would be driven out again, and consequently there would be no compressed charge in the crank-chamber at the end of such working-instroke, whereas 60 during the following instroke, when the rod L would be in the lowered position, the valve would remain closed, so that the before-described supplemental charge would then be formed. For the second above-mentioned 65 case, where the supplemental charge is to be omitted, the valve g' would be arranged as shown at Fig. 6, it being held closed by a spring during the working-instroke of the piston, so that the preliminary compressed charge 70 would be formed, while during the following instroke, when the rod L would be moving downward, this is caused to press the valve open, so that the charge previously drawn

into the crank-chamber would be forced out again. When working with petroleum, the gas-passages must be modified in proportion to the heating-power thereof.

5 The advantages resulting from this construction of motor-engine are, that by means of the purer combustible mixture and the large volume of the charge a more effectual combustion takes place, and that, on account of the greater 10 speed here attainable, less loss of heat takes place, resulting in a decreased consumption of gas, and, lastly, that with this arrangement the cheaper carbonic-oxide gas—for instance, the so-called "Dowson" gas—may be used 15 with advantage.

I do not herein claim the apparatus shown and described for carrying my method into effect, as such constitutes the subject-matter of my application, Serial No. 177,713, filed 20 September 21, 1885.

Having thus described the nature of my invention and the best means I know of for carrying it into practical effect, I claim—

1. In a gas or petroleum motor engine every 25 alternate instroke of which is a working-stroke, the method of introducing into the cylinder, first, during the outstroke following the working-instroke, a preliminary charge of combustible mixture or air through the piston, 30 whereby the residual products of combustion are expelled; secondly, during the following instroke, the main charge of combustible mixture, and, thirdly, at the end of the said instroke, a supplemental charge of combustible 35 mixture or air admitted through the piston, the said combined charges being then further compressed by the following outstroke and ignited, substantially as herein described.

2. In a gas or petroleum motor engine every 40 alternate instroke of which is a working-stroke, the method of introducing into the cyl-

inder, after the main charge, a supplemental charge of combustible mixture or of air admitted through the piston at the end of the suction-instroke, the combined charges being 45 then compressed by the following outstroke and fired, substantially as herein described.

3. In a gas or petroleum motor engine every alternate instroke of which is a working-stroke, the method of introducing into the cylinder, before the main charge, a preliminary charge of combustible mixture or air admitted through the piston, whereby the residual products of combustion are expelled from the cylinder before the admission of the main 50 charge, substantially as herein described.

4. In gas-motor engines wherein the ignition of the charge is effected by its compression in contact with a heated surface, the method of retarding the ignition till the crank is at or 60 about the dead-center by introducing into the admission-passage a charge of combustible mixture weaker than that contained in the cylinder, substantially as herein described.

5. The method of regulating the speed of the 65 engine by causing the discharge valve for the products of combustion to remain closed when the speed is too great, so that the products of combustion are retained under pressure in the cylinder, and no fresh charge is consequently 70 admitted until the speed is again reduced and the discharge-valve opened, substantially as herein described.

In testimony whereof I have signed my name to this specification, in the presence of two 75 subscribing witnesses, this 10th day of April, A. D. 1885.

GOTTLIEB DAIMLER.
